UNITED STATES PATENT OFFICE.

MARTIN E. ANDERSON, OF TAKOMA PARK, MARYLAND.

SAFETY CRANKING DEVICE FOR GAS-ENGINES.

1,369,952.

Specification of Letters Patent.

Patented Mar. 1, 1921.

Application filed August 19, 1920. Serial No. 404,625.

To all whom it may concern:

Be it known that I, MARTIN E. ANDERSON, a citizen of the United States, residing at Takoma Park, in the county of Montgomery and State of Maryland, have invented certain new and useful Improvements in Safety Cranking Devices for Gas-Engines, of which the following is a specification.

This invention relates to a safety cranking device for starting explosive engines, the object of the invention being to provide a simple, reliable and effective device of this character, which, in the event of the engine back-firing while being cranked, will automatically disconnect the crank handle and positively prevent it from rotating backwardly to any considerable extent, thus preventing injury to the operator.

The invention consists of the features of construction, combination and arrangement of parts hereinafter fully described and claimed, reference being had to the accompanying drawing, in which:—

Figure 1 is a side elevation of the device partly broken away.

Fig. 2 is an end elevation taken on line A—A, Fig. 1.

Fig. 3 is a fragmentary side elevation partly in section showing the relation of the parts after the device has operated, and

Fig. 4 is a front view of an automobile showing how the device is attached thereto.

Referring to the drawing, 1 represents a stationary bearing, which may be part of the engine frame or part of the frame work of an automobile; slidably and rotatably mounted in bearing 1 is a shaft 2 provided at one end with the usual ratchet member 3 for engaging the crank shaft of the engine.

Near the other end of the shaft and rigidly connected thereto is a disk like member 4 having a flange 5, through which flange and the shaft 2 there passes a pin 6. The disk 4 may, of course, be rigidly secured to the shaft 2 by any other suitable means. The disk 4 is provided with one or more holes 7 for a purpose to be hereinafter described. On the end of the shaft 2 which projects beyond the flat surface of disk 4 is rotatably and slidably mounted a ratchet driving member 8 having a hub 9 and a number of peripheral ratchet teeth 10 provided with beveled portions 11. Secured to the hub 9 is a crank 12 of any desired shape. The ratchet disk and crank are resiliently secured in

place on the shaft 2 by means of a spring 13, one end of which is secured to the crank by means of screws 14 while the other end passes through an opening 15 in hub 9, and engages with an annular groove 16 in the end of shaft 2. The tension in spring 13 tends to force the flat face of the ratchet member against the corresponding surface of disk 4. Carried by the ratchet 8 is one or more pins 17 arranged to engage with the openings 7 in disk 4. Rotatably secured to the disk 4 by means of the overhanging hook like portion 18 and plate 19 is a plate 20; this plate has a downwardly projecting portion 21 whose surface lies substantially in the plane of the front surface of disk 4. Carried by the portion 21 and pivotally connected thereto by means of a rivet 22 is a pawl 23 having a wedge shaped point 24 terminating in a stop or projecting portion 25. The pawl 23 is resiliently held against the ratchet teeth 10 by means of a spring 26, secured to the pawl and downwardly projecting portion in the manner shown. To prevent the plate 20 from rotating it is anchored to the stationary parts of the framework of the engine or automobile by some suitable means. In the drawing I have shown a rod 27 as performing this function, one end being secured to the downwardly projecting portion 21 and the other to the framework of the automobile in the manner indicated in Fig. 4.

The tension of the spring 13 can be adjusted by means of the screws 14 in a manner which is apparent from the drawing.

The operation of the device is as follows: The crank handle is grasped and the shaft 2 shoved toward the engine until the ratchet 3 engages with the coöperating pin in the crank shaft and then the necessary force is applied to turn the engine. The pawl 23 will permit the ratchet teeth 10 to rotate freely in a clockwise direction, but in case the ignition point should be too far advanced and the explosion take place at such a time that the engine would tend to move in a counter-clock-wise direction, the ratchet teeth 10 will move toward the point 24 of the pawl 23 and then continue to ride up the inclined surface of the pawl until the ratchet member 8 becomes separated from the disk 4 a sufficient distance to permit the pin or pins 17 to disengage the openings 7 and thus disconnect the crank from the ro-

tating disk 4. When the tooth 10 has moved up the inclined surface of the pawl the distance required to withdraw the pin 17 from the hole 7, the tooth then encounters a stop 25 which positively prevents any further backward rotation.

From the above description it is seen that my means of my improved cranking device the danger of having the hand or arm of 10 the operator injured or broken by the back-firing of the engine is entirely removed. There will, of course, be a slight reverse movement of the crank handle as it is necessary that it move counter-clock-wise 15 through a sufficient arc to allow the pawl to accomplish the necessary disconnection, but the crank cannot continue in its reverse rotation because it encounters the stop 25.

The cranking device is shown attached to 20 an automobile, in Fig. 4, but it is as well adapted to be used with any explosive engine, and it should especially be employed in connection with tractor engines and on trucks, where the operator is obliged to employ both his hands and all his strength to 25 turn the engine.

Since the cranking device shown and described is a unitary structure, it can be used as well on cars where the crank is removed 30 from the front of the machine, as on those cars having the crank permanently attached thereto, the only requirement being that the disk 20 be anchored to the framework so as to prevent rotation.

35 I am aware that similar devices have been invented and patented, and I do not claim the idea in its broadest aspect, but I do desire protection for such features of construction as are not present in the prior art and 40 which distinguishes my invention therefrom.

I claim as my invention—

1. A driven member comprising a shaft, a circular disk secured thereto; said disk being 45 provided with one or more openings, a driving member rotatably and longitudinally movable with respect to said disk; resilient means for causing said driving member to engage the surface of said disk, means 50 carried by said driving member for engaging the openings in said disk and for preventing relative rotation of the disk and driving member, a plate rotatably connected to said disk, a pawl pivotally attached to 55 said plate and engaging the surface of said disk, ratchet teeth on the peripheral surface of said driving member, resilient means for forcing said pawl into contact with said ratchet teeth, means for preventing the rotation 60 of said plate and pawl, and means on said pawl for disconnecting the driving member from the disk and permitting rela-

tive rotation of the driving member and disk whenever reverse rotation takes place. 65

2. In a device of the class described, a shaft, means at one end for attachment to the shaft of a rotatable member, a circular disk near the other end of said shaft and non-rotatably connected thereto, a driving member rotatably and slidably connected to 70 the end of the shaft projecting beyond said disk, resilient yielding means for securing said driving member to said shaft and for forcing said driving member toward the face of said disk, openings in said disk, and 75 means on said driving member engaging with said openings to prevent relative rotation of said disk and driving member, a series of ratchet teeth around the periphery of said driving member, a pawl pivotally 80 connected to said plate, and lying against the surface of said disk, resilient means attached to said pawl and plate whereby said pawl is held against the ratchet teeth of the driving member, means for preventing rotation of said plate and means comprising said pawl and ratchet teeth for disconnecting the driving member from the disk whenever the driving member is forced to rotate in the reverse direction. 90

3. A driven member, a circular disk non-rotatably secured thereto, said disk being provided with one or more openings, a driving member rotatably and slidably attached to said disk, resilient means for causing said driving member to engage the surface of said disk, means carried by said driving member for engaging the openings in said disk to prevent relative rotation of the driving member and disk, a plate rotatably connected to said disk a pawl pivotally attached to said plate and extending over the face of said disk, said pawl being provided with a wedge shaped point, ratchet teeth on the peripheral surface of said driving member, resilient means for forcing said pawl against said ratchet teeth, means for preventing the rotation of said plate and pawl, whereby the wedge shaped point of said pawl will be forced between the disk 110 and the driving member upon reverse rotation of the latter for the purpose of separating the driving member from the disk sufficiently to cause disengagement of the connecting means. 105

4. A device in accordance with claim No. 3, in which the pawl is provided with a projecting stop. 115

5. A device in accordance with claim 4, in which the ratchet teeth are each provided with a beveled portion. 120

In testimony whereof I have affixed my signature.

MARTIN E. ANDERSON.
